UNITED STATES PATENT OFFICE.

CHESTER COMSTOCK, OF RIDGEWOOD, NEW JERSEY, ASSIGNOR OF ONE-HALF TO
CHARLES LEFFLER, OF BROOKLYN, NEW YORK.

CENTRIFUGAL PUMP.

1,084,928.

Specification of Letters Patent.

Patented Jan. 20, 1914.

Application filed April 19, 1911, Serial No. 621,969. Renewed June 11, 1913. Serial No. 773,142.

To all whom it may concern:

Be it known that I, CHESTER COMSTOCK, a citizen of the United States, residing in Ridgewood, in the county of Bergen and State of New Jersey, have invented certain new and useful Improvements in Centrifugal Pumps, of which the following is a specification.

One of the principal objects of my present invention is to furnish a centrifugal pump so constructed and organized as to supply the discharge of one pump mechanism directly to the interior of a second pump member. Another object of my invention is to furnish a centrifugal pump so organized that the impellers are substantially housed in, thereby taking better hold of the fluid, doing away with a percentage of slip, and thus increasing the efficiency and adding to the centrifugal force of the fluid contained within the revolving chambers. These impeller chambers receive the fluid at a point near their center and by revolving them at a practical rate of speed the fluid entering therein is given a centrifugal impulse and the pressure caused thereby forces the fluid through ports to be hereinafter described in detail and against fixed directing members. These directing members are in the form of disks having guides or blades placed thereon which cause the fluid to return immediately to the center, resolving the centrifugal force, and the force of the speed of rotation, into one of internally directed velocity. This velocity and its consequent pressure may be then taken to exhaust, or as in the present instance, into a succeeding like impelling unit, there going through a similar cycle as that above described. From the foregoing it will be seen that in a series of these units each impeller chamber with its directing member forms a complete centrifugal pump unit, and its discharge is directed from the outlet on one member of the series directly to the inlet of the succeeding member of the series.

In the drawings accompanying the description, Figure 1 is a sectional view of a pump with two unit impellers, taken on the line 1—1, Fig. 2. Fig. 2 is a sectional view taken on line 2—2, Fig. 1. Fig. 3 is a front view on the inlet side of the impeller member with a portion broken away showing the interior thereof. Fig. 4 is a sectional view

taken on the line 5—5, Fig. 5. Fig. 5 is a view of the impeller member looking at the exhaust side. Fig. 6 is a front view of the stationary fluid-directing member showing the fluid-directing guides thereon. Fig. 7 is a sectional view of the fluid-directing member taken on the line 7—7, Fig. 6. Fig. 8 is the opposite side of the fluid-directing member.

Like references in the drawings and specification refer to like parts throughout.

The present improvements are illustrated in the accompanying drawings as being embodied in a duplex centrifugal pump in which the mechanism is inclosed in a casing and the impellers are keyed on a shaft, usually arranged horizontally. In this form of the improvement, as shown in Figs. 1 and 2 for instance, the frame or casing has the base portion 1, the substantially cylindrical inclosing walls 2, the end plate or head 3 at the left hand in Fig. 1, the opposite end plate or head 4 at the right hand end in Fig. 1. The left hand head 3 is shown formed with a space 5 for receiving the suction pipe 6 and thus supplying the fluid to the annular inlet space at 7, to the first impeller 8. The impellers 8 and 9 are shown mounted on a shaft 10 which at the left hand is carried in the bearing 11 which may be (as indicated herein) formed on the head 3 of the pump. This left hand bearing 11 is shown provided with a stuffing box 12 chiefly for preventing the admission of air; this packing box may be of any usual or proper construction, and is herein shown as comprising the packing material 13, a gland 14, and the nut 15. The right end of said shaft 10 is shown carried by a bearing on the right hand head 4 of the pump. This right hand head is shown provided with a chamber space 16, which is tightly closed by the cover 17, whose outer rim 18 is shown screwed on to the projecting wall 19, within which said space is formed, as will be clearly understood from Fig. 1. At this end thereof the shaft 10 is furnished with some suitable collar or device for taking the end thrust, to such an extent as may in any particular instance be desirable in practice. In this instance I have shown the shaft provided with a threaded nut 20 held by a check-nut 21 and bearing against one of the tracks of a ball bearing and the balls being shown controlled by a controller or supporter in a well known manner. right hand head is also shown provided with a space 22 into which the water or other fluid is discharged by the second impeller 9, and thence passes out through the discharge 5 pipe 23.

During the operation of the machine, the water is drawn into the first impeller 8 through the annular space 7, where this impeller is fitted to run closely against the rim 10 24 of the head 3, and then passes outward through the interior space 25 of the impeller, which, it will be noted is in the nature of a space-inclosing revolving member; the detail construction of which is more 15 fully illustrated in Figs. 3, 4 and 5. The water being received within the space 25, within the impeller 8, is taken up by the radial walls 26 and caused to revolve with the impeller by which means the water or 20 fluid is forced outwardly with a pressure due to the velocity of rotation, with the result that the fluids tend to pass out through the narrow space at 27, Figs. 1 and 4, at which point the extended portion 28 of the 25 impeller runs closely, but freely, around the outer ends of concentrating wings 29 (see Figs. 1, 6, and 7), whereby the fluid is caught by the curved outer ends 30 of said wings 29 and is gradually guided inwardly 30 toward the center of the machine and is finally discharged through the middle annular passage-way 31 into the second impeller 9. The concentrating wings 29 are carried on the middle plate or member 32 35 and this member being so located as to bring the end faces of the wings close to the right hand surface of the wall 33 of the impeller. The water is thus guided along next to said wall and between the concentrating guides 40 and so is brought to a comparative state of rest as regards rotation as it passes to the next succeeding impeller. This operation, it will be observed, may be repeated any desired number of times by simply providing 45 the pump with a sufficiently extended series of impellers.

For holding the wing plate 32 in proper position the outer edge of this plate is shown engaging between two members 34 and 35 50 which extend respectively, to engage one of them with the left hand head and the other of them to the right hand head or against another wing member 32, whenever this is used.

55 In the present instance, the impeller members 8 and 9 are shown having only three wing members 26, and 26', but a different number may be used. I deem it to be desirable in practice to provide an intermediate series of short wing members 36 placed intermediate of the main wing members 26 and 26'. These members 36 are comparatively short and only bridge the opening 27. These short wing members 36 are 60 for the purpose of aiding the main mem-

bers 26 and 26' in presenting the fluid for the action of the concentrating wings 29.

The impeller 8 receives the fluid at a point near the center, as 7, and the fluid on entering the interior of the impeller passes outwardly between the impeller wings or walls 26, as indicated by the arrow-line 37 and is then carried sidewise as indicated at 38, until it reaches the discharge point, as 27, where the discharge takes place toward the 75 axis of the impeller. For this purpose the impeller is carried sidewise to form the overhanging portion as 28 so that the discharge opening at 27 lies between the inner edge of the wall 32 and the outer edge of 80 the disk or wall 33. This construction causes the flow or discharge to take place toward the axis of the impeller and this inwardly turned flow which is kept within the plane of the overhanging portion 28, is 85 caused without loss of energy and it is so directed from the rotating impeller member.

Heretofore a large proportion of centrifugal pumps have discharged from the impeller radially outward, either with or without "diffusion blades" so called, and if the pump was of the multistage type the transmitted fluid was taken from one impeller discharging outwardly to the centrally located inlet port of the next impeller. The 95 transmitted fluid has, therefore, at the discharge an outward flow of considerable velocity, next a lateral flow or one parallel with the axis of the pump, and then, an inward flow or one toward the axis of the 100 pump.

In accordance with well known physical laws, the tendency of any moving object is to continue its motion in a direct line unless deflected therefrom by some obstruction 105 or force outside of itself. Heretofore in centrifugal pump construction the flow of water in a direct line is obstructed by the guiding surfaces which are interposed to cause a deflection of flow, and a surface 110 friction is developed similar to that which has always existed between a flowing body of water and the surface which incloses and guides the same, is the negative element 115 which operates to cause the loss of the energy which had been previously imparted to the water by the impeller. The more abrupt these changes of direction are the greater will be the loss of energy arising from the change of direction of the flow. The more gradual the change of direction, the longer must be the passages through which the water must flow, and the greater the surface friction that will inevitably result. A comparison of the construction of pumps in 120 which the discharge is from the impeller outward with that shown in this application reveals the following points of vital difference.

125 In the former construction the flow of the 130

water was first outward from the impeller, then lateral, and then inward; these changes taking place after the water has left the impeller in passageways that are relatively 5 long and in which the current of water is thin and the volume small in proportion to the inclosing surfaces, so that the amount of surface friction is proportionally great. The sum total of the energy required to 10 make these changes of direction and to overcome the friction must be taken from the energy held in the water at the moment of discharge from the impeller. And further, little or no benefit can be secured from the 15 momentum of the water as distinguished from the centrifugal force except at a great increase of surface friction. These are well known facts in centrifugal pump construction, and are in accordance with the well 20 known laws governing the flow of water.

In my present construction the changes of direction which are made necessary whenever centrifugal force is applied in a multi-stage pump, are all fully accomplished while 25 the water is within the impeller and under conditions which secure the same amount of stored energy in the water at the point of discharge as in the case of the impeller discharging outwardly, provided the peripheral space of the two impellers is the same.

Advantage can also be fully taken of the momentum of the water arising from the space of rotation which is available at the moment of discharge from the impeller, for 35 the guides are of such a shape and so placed as to make possible an increase of efficiency by virtue of the momentum of the water as it comes within their guiding influence at the instant of discharge.

40 The passageways formed by the guides conduct the water by the shortest possible course to the inlet port of the next impeller and are of increasing sectional area in the direction of the flow, and of such shape that 45 the surfaces present the minimum amount of surface friction in proportion to the volume of water.

One of the leading features of my present improvement is the combination with the inwardly directed discharge from the impeller 50 at the point 27 of a series of guides or concentrators as 29 by which the fluid is received at the line of the discharge 27, upon rearwardly projecting points or blades 30, 55 whose extreme outer ends lie close to the path of the impeller blades at 27, and conduct the same inwardly toward the axis of the mechanism to about a point 31, where the fluid will be guided through the passageway 31 into the second impeller 9. In 60 this arrangement it will be noted that there is a direct co-action between the inwardly discharging impeller 36 and the outward curved ends or points 30 of the blades 29, 65 whereby these blades act to take away the

fluid from the point 27 and by means of the momentum of said fluid direct the same inwardly toward the point or line 31. By the above construction it will further be seen that the altering or changing of direction of 70 the fluid in said impeller members at the point 27 is done entirely within the body of said rotative impeller.

It will be also noted that the blades 29 are brought closely against the outer surface 75 of the wall 33, so that they form in combination with the plate 32, on which said blades are mounted and said wall 33, a series of closed channels or passages 37, Fig. 6, whereby the fluid is all conducted away 80 from the point 37 and is finally all discharged at the inner circle 31, the said passage-way 31 leading into the interior of the next successive impeller of the series of such impellers.

Having thus described my invention, I claim:

1. A centrifugal pump so organized as to supply the discharge of the impeller of one unit thereof to the centrally located inlet 90 port of the impeller of the next succeeding unit by causing the transmitted fluid while within the impeller to flow toward the axis of the impeller before it passes the point of discharge of the said impeller.

2. A centrifugal pump so organized as to supply the discharge of the impeller of one unit thereof to the impeller of the next succeeding unit by causing the transmitted fluid while within the impeller to flow toward the axis of the impeller before it passes the point of discharge of the impeller, and from this point of discharge to cause a further continuous flow toward the axis of the impeller by fluid directing 100 guides organized to coöperate with the impeller for the purpose described.

3. In a centrifugal pump, a series of pump units, each pump unit consisting of an impeller having a centrally located inlet 110 port, a discharge port located near the periphery of the impeller having its point of discharge directed toward the axis of the impeller, and a stationary member having fluid directing guides integral with one side thereof and projecting therefrom, the said unit being so organized that the outer ends of the fluid directing guides are diametrically within the point of discharge of the impeller and in close proximity thereto, the 120 said disk having a centrally located passageway therethrough to serve as an outlet port for the pump unit.

4. In a centrifugal pump, a plurality of pump units, each pump unit consisting of 125 impeller blades contained within a rotatable housing, said housing having a central inlet port and an outlet port, said outlet port arranged to form an overhanging extension of said housing and having its point of dis- 130

charge directed toward the axis of said rotatable housing, and a stationary disk having curved fluid directing guides thereon, said guides having relatively thin front edges on their outer ends which are diametrically within the point of discharge of the impeller and in close proximity thereto.

5. In a centrifugal pump, a rotatable impeller member comprised of a housing having impeller blades therein, said housing having an inlet and an outlet port and being recessed on the outlet port side and adapted to receive the inlet end of a stationary disk having concentrated or guiding blades thereon.

10 6. In a centrifugal pump, a stationary fluid-directing member comprised of a disk having a plurality of directing guides integral thereon and having an annular seat 20 near the outer edge thereof to receive a corresponding extension of its related rotating impeller, forming with the said impeller a complete impeller unit for the purpose described.

25 7. In a centrifugal pump, a stationary fluid-directing member comprised of a disk having a plurality of directing guides integral thereon and having an annular seat near the outer edge thereof to receive a corresponding extension of its related rotating 30 impeller, forming with the said impeller a complete impeller-unit for the purpose described, said impeller adapted to discharge, from a point near the outside on one side 35 thereof, toward the center.

40 8. In a centrifugal pump, a stationary disk having curved directing guides thereon, said guides having relatively thin front edges on their outer ends, whereby they 45 present a minimum cutting edge to the in-rushing discharge.

45 9. In a centrifugal pump, an impeller comprised of a rotatable housing having a hub and containing impeller wings dividing said housing into a plurality of chambers, a central inlet port leading into said chambers and an outlet port forming an over-

hanging extension with the outer diameter of said housing, said outlet port containing a plurality of short impeller blades placed intermediate of said impeller wings for the purpose set forth. 50

10. In a centrifugal pump, an impeller unit comprised of a rotatable housing having a hub and containing impeller wings 55 dividing said housing into a plurality of chambers, an inlet port into said chambers, a seat on the outlet port side adapted to receive therein a fluid-directing disk, said seat forming with the outer rim of said housing 60 at their junctures an overhanging annular extension, said extension having therein an annular discharge port so organized that the fluid is directed toward the center of the stationary disk, said annular discharge 65 port containing short impeller blades placed intermediate of the said impeller wings, and a stationary fluid-directing disk having on one side thereof curved directing fluid-guides, said directing fluid-guides being located on said disk to receive the discharge 70 fluid and direct it toward the central inlet of the succeeding impeller, for the purpose described.

11. In a centrifugal pump, impeller 75 blades contained within a rotatable housing, said housing containing a central inlet port and an outlet port arranged to form an overhanging extension of said housing having its point of discharge directed toward 80 the axis of said rotatable housing.

12. In a centrifugal pump, an impeller having a discharge port located near the periphery of the impeller, the said impeller being so organized as to cause the transmitted fluid, while within the impeller to flow toward the axis of the said impeller before it passes the point of discharge from the impeller. 85
